TRANSFORMER CONSTRUCTION AND
WINDINGJohn C. Joost, New York, N. Y., assignee to
Edwards and Company, Inc., Norwalk, Conn., a
corporation of New York

Application November 3, 1938, Serial No. 238,508

15 Claims. (Cl. 175—356)

This invention relates to transformer construction, more particularly of the low voltage and relatively small capacity type such as is used for operating low voltage devices, such as door bells, buzzers, relays, low voltage appliances, and the like, from the higher voltage of a household lighting circuit usually of 110 volts, and concerns particularly the winding and core assembly of transformers of this general character.

One of the objects of this invention is to provide an inexpensive, practical and reliable insulating and foundation structure for winding the coil or coils and for mechanically anchoring and electrically connecting terminal conductors to the end or ends of the winding or windings. Another object is to provide a coil or winding construction that may be constructed commercially at less cost than has heretofore been possible with known methods or types of construction, and also to improve the electrical and mechanical efficiency of structures of this kind. Another object is to provide a construction of the above-mentioned character in which assembly of the various parts may be inexpensively and quickly carried on and in which strength of structure and reliability of action are achieved in a simple and effective way. Another object is to provide a core or bobbin for supporting the coil or coils or upon which the coil or coils may be wound, that will be simple, inexpensive, strong, durable and well adapted to withstand the handling accompanying quantity production thereof.

Another object is to provide a dependable and inexpensive form of mechanical anchorage of relatively heavy terminal conductors for electrical connection with windings of fine or small or fragile wire, and thus to reduce breakage or damage in course of manufacture and in course of handling, as well as in subsequent use of the completed winding or device. Another object is to provide a simple, strong and reliable assembly of winding and core and of the terminal connection or connections of the winding, and capable of being carried out in a rapid, efficient and yet simple manner in actual practice. Other objects will be in part obvious or in part pointed out hereinafter.

The invention accordingly consists in the features of construction, combinations of elements, arrangements of parts, and in the several steps and relation and order of each of the same to one or more of the others, all as will be illustratively described herein, and the scope of the application of which will be indicated in the following claims.

In the accompanying drawing in which is shown a preferred one of the various possible embodiments of the mechanical features of my invention,

Figures 1, 2 and 3 are plan views of top, side and end members, respectively, of a winding support or bobbin;

Figure 4 is a perspective view of a conductor-anchoring member;

Figures 5, 6 and 7 are respectively top, front and end elevations of the assembled winding support or bobbin;

Figures 8 and 9 are plan views of illustrative forms or shapes of laminations that may be used in making up the core;

Figure 10 is a top plan view of the final transformer assembly, including the core, windings, winding support and terminal-conductor mountings or anchorages;

Figure 11 is a fragmentary central sectional view as seen along the line 11—11 of Figure 10.

Similar reference characters refer to similar parts throughout the several views in the drawing.

For purposes of better illustration of certain features of my invention, let it be assumed that a coil or coils are to be related to an iron core, such as, for example, the middle leg 20 (Figures 10 and 11) of a transformer core 21, illustratively of the shell type, and made up of laminations 30 appropriately shaped to be pieced together, such as the laminations 22 and 23 of Figures 8 and 9, respectively. The winding should be dependably supported on the middle leg 20 and well accommodated within the core windows 24 and 25. 35

In such case, I make up a winding support or bobbin, preferably out of parts of sheet insulating material, like fiber, hard rubber, or the like, preferably shaped and conformed as shown in Figures 1, 2 and 3 which are plan views of parts 40 26, 27 and 28, respectively, the winding bobbin being preferably so constructed that two of each of these three parts are employed in making it up.

These parts, moreover, are shaped so that they may easily and inexpensively be punched out of strip or sheet stock and preferably the part 28 which is to function as an end member is of heavier stock than the parts 26 and 27 which can be of the same gauge or thickness.

The part 28 is in general four-sided, though its corners may be beveled or cut off, as shown, and it has stamped out of it a central hole 29, also preferably four-sided, particularly where the core part 20, as in the above-described type of transformer core, is in cross-section four-sided 55

and approximates a square. The hole 29 is dimensioned to be slightly greater than the cross-section of the core and sufficiently so to accommodate the thicknesses of the parts 26 and 27 and preferably, also, another part 30 of Figure 4 to be described later.

The part 28 is provided in two opposed sides of the aperture 29 with centrally disposed preferably rectangular recesses 31 and 32, and is preferably also pierced at appropriate points to permit the passage therethrough of the ends of the wires of which the winding is to be made. Thus, I may provide two relatively small holes 33 and 34, one positioned close to the hole 29 and the other positioned near the outer periphery of the part 28, and two holes 35, 36 which may be larger and also appropriately positioned, for example, as indicated in Figure 3.

In making up and assembling the bobbin, two end members 28 are employed and they first have related to them two members 26 which are placed so as to rest adjacent their ends against the straight or unrecessed edges 37, 38, respectively, of the hole 29 in the two end members.

The member 26 is in general wider than the length of the edge 37 or 38 of the end member 28, and along its longitudinal edges it is cut away to provide opposed pairs of recesses or notches 39, the bottoms of each pair being spaced by the dimension equal to the length of the edge 37 or 38, and also preferably a single pair of elongated notches 40, 40 whose bottom edges are spaced from each other by preferably the same dimension.

Two members 26 may thus be passed into the holes 29 of two end members 28, the latter being appropriately held spaced from each other (see Figure 5), the wider end portions of the members 26 being passed preferably along a diagonal of the holes 29; the members 26 may then be moved or swung to bring one of them against the edges 37, 37 of the holes 29 of the two members 28, and the other one against the edges 38 thereof, appropriate portions of the members 28 taking into and snugly fitting in the opposed notches 39 whose width closely matches the thickness of the members 28. In Figure 5 this relationship is clearly shown. This assembly may be achieved in any suitable way and if desired a mandrel (not shown) may be slid into position between the two members 26 to hold them in spaced relation from each other and to facilitate assembly of the remaining parts.

The remaining parts preferably comprise two members 27, shaped as shown in Figure 2. The member 27 is generally rectangular and at its narrow ends is provided with tongues 41, 41 dimensioned to snugly fit into the recesses or notches 31, 32 in the opposed edges of the hole 29, and in its opposed longitudinal edges is provided with tongue-like extensions 42, 42 dimensioned to be snugly received in the notches 40 of the members 26.

With two end members 28 and two side members 26 assembled as above-described, two members 27 may now be assembled to the above-described sub-assembly, and this may be done by first entering one end tongue 41 into a notch 31 or 32 of one end member 28, and for that purpose a snugly fitting mandrel, as above described, is helpful; in Figure 5 I have indicated in dotted lines such an initial position of a member 27 with one end tongue 41 thus entered into a notch in the left-hand end member 28. Then the member 27 may be swung in clockwise direction and

pressed downwardly to snap its opposed end tongue 41 into the notch in the member 28, the parts yielding sufficiently, even though they snugly interfit, for this purpose, whence the longitudinal tongues 42, 42 enter and rest in the notches 40, 40 of the two members 26. The other member 27 may be put into place in the same way, resulting in a structure better shown in Figures 5, 6 and 7.

The resultant structure is unitary, rigid, free from play, strong, and has its parts dependably interlocked so that all are held in place and each contributes to maintaining rigidity of construction. The notches 39 of the two members 26 hold the end members in spaced relation, members 27, with their tongues 42 fitting into the notches 40 of the members 26, and in fact with the contiguous appropriately configured edges of the members 26 and 27 in mutually overlapping relation, hold the members 26 against movement toward each other while this interrelationship causes the members 26 to hold the members 27 against movement toward each other. The tongues 41 of the members 27, in taking into the notches 31, 32 of the end members, cause the latter to hold the members 27 against outward movement and thus to insure the maintenance of the above-described mutually overlapping relationship of the contiguous edges of the members 26 and 27. Also, the end edges of the members 27 to either side of the tongues 41 are butt-ended against the faces of the members 28 and thus prevent the right-angled relationship between the end members 28 and the members 26 from being changed.

The construction is light yet very strong and the individual parts are easily and inexpensively stamped and assembly is simple and rapid, it being noted that I make it possible to eliminate the use of tools or securing devices or other cumbersome means of fastening or securing. The interlocking or mutual overlapping of the contiguous edges of successive members 26 and 27 also insures that throughout the length thereof no inward yielding takes place particularly under any tensioning or tightness of insulated wire as the latter is subsequently wound onto the bobbin and between the end members 28; the latter also are dependably held against movement away from each other and thus dependably resist any tendency on the part of the wire being wound to push them outwardly.

Upon the resultant bobbin and between the end members 28, the coil or coils may now be wound. Where the device is to function in a transformer, as above described, two coils are wound on the bobbin, one of them, the high voltage winding, usually 110 volts, being usually of relatively fine wire which, depending upon design and power requirements, may range, for example, from No. 25 to No. 40, or so. This winding is preferably wound onto the bobbin first and any standard or usual practice may be employed in the winding process. One end of the winding is preferably brought out through a hole 33 (Figures 3 and 7) in one end member, and when the required number of turns is wound, the remaining end is brought out through a hole 34 in the opposite end member.

The low voltage winding usually comprises less delicate or fragile wire and a lesser number of turns. Either winding may be wound first and illustratively the low voltage winding may be wound on top of the high voltage winding, again using any standard or known practices in effect.

ing the winding and superimposition of one winding in layers upon the other. Being of heavier wire, the ends of the low voltage winding are brought out through an opening 35 in one end member and an opening 36 in the other end member, it being noted that these openings are larger to accommodate the heavier wire, suitable lengths of end portions being left free for ultimate connection to appropriate binding posts 10 (not shown).

The ends of the low voltage winding are brought out through the above-described openings, but the latter are so positioned and selected that the wire ends come out below the lower 15 member 26, as viewed in Figures 6 and 7, while a similar selection is made of the smaller openings to bring the fine and delicate ends of the high voltage winding out above the upper member 26, as viewed in Figures 6 and 7.

Now one of the difficulties heretofore encountered and which my invention effectively and dependably overcomes is the connection of these fine end wires to suitable and heavier terminal conductors or wires, usually heavily covered with 25 insulation. Heretofore such difficulty has included not merely coping with the delicacy of the operation but also with the mechanical obstacles presented and which frequently resulted in breaking of the fine wire. Having completed the 30 structure as thus far described, noting first that the end edges of the members 26 are provided with notches 44 of a depth such that their bottoms are appropriately spaced from the outer faces of the end members 28 (see Figure 5), I 35 next put into position the member 30 of Figure 4; that member is preferably made of sheet metal, is generally rectangular, and is provided with upwardly bent tongues 45 of suitable width, the notches 44 being of a width snugly to accommodate 40 the tongues 45.

Member 30 is slid into the hollow bobbin and brought flush up against the upper member 26 to the outer side of which the fine wire ends of the high voltage winding extend, the tongues 45 45 passing upwardly through the notches 44 so that they project upwardly from the two end portions of the member 26, as is clearly shown in Figure 6.

Suitable lengths of heavy wire, usually No. 14, 50 usually heavily insulated as is typical of 110-volt circuits, as indicated at 46 in Figure 10, are now provided but with their extreme end portions 47 bared; they are so placed as to bring them in between the ears or tongues 45 and the end members 28 and thus rest against the member 26 which, it 55 is to be noted, is backed up on its under side and including those portions thereof that project beyond the end members 28 by the main body part of the sheet metal member 30. This relationship is also well shown in Figure 11. The tongues 45 60 are now bent over and down upon the insulated conductors 46, respectively, by any suitable means, and sufficient pressure is applied so that the insulated conductor is securely clamped between the tongue and the sheet metal part 30, thus giving this relatively heavy and stiff conductor a strong and durable mechanical anchorage and holding the bared ends 47 rigidly against displacement or movement. The same operation 65 70 also fixes the member 30 in position which, as shown in Figure 11, becomes inescapably interlocked with the member 26.

To these bared ends the bared end portions of the fine wire ends of the high voltage winding 75 are now soldered, as indicated in Figure 10, pref-

erably first taking a few turns of the fine wire about the bared end portions of the heavy wire. The resultant electrical connection is, due to the strong mechanical anchorage of the heavy terminal wires 46, safeguarded against breakage, particularly during the subsequent handling of the assemblage.

The assemblage may now be assembled to the core which, as above noted, may take the form of the shell type where the winding is to function 10 in a transformer, the core being usually laminated and assembled out of appropriately shaped laminations like the laminations 22 and 23 of which the lamination 22 provides the middle core leg 20, it being understood, of course, that 15 the laminations 22 are assembled to the completed winding structure alternately from the two ends of the latter. Thus, one lamination 22 has its core leg 20 entered into the hollow bobbin from one end thereof, while the next lamination 20 22 has its core leg 20 entered into the bobbin from the opposite end of the latter, a lamination 23 in each instance completing the individual magnetic circuits. The core may thus be built up to the desired extent, preferably snugly to 25 fill up the space within the bobbin, suitable wedging means being employed, if desired, to secure tightness of ultimate interfitting. The core may thus be made to coact with the parts of the bobbin to hold the parts assembled. 30 Thereafter, the completion of the transformer construction may be carried on in any suitable way, as by providing a suitable casing or mounting therefor.

Thus, it will be seen that there has been provided in this invention a winding support and winding structure and transformer construction in which the various objects hereinbefore noted, together with many thoroughly practical advantages are successfully achieved. It will be seen 40 that the construction is simple, inexpensive, and thoroughly dependable in action and well adapted to meet the conditions of hard practical use. Bobbin parts can be inexpensively stamped, as is also true of the sheet metal part 30 of Figure 4, 45 and it will be seen that assembly thereof can be carried on quickly and inexpensively and with thoroughly reliable results.

As many possible embodiments may be made 50 of the mechanical features of the above invention and as the art herein described might be varied in various parts, all without departing from the scope of the invention, it is to be understood that all matter hereinabove set forth, or 55 shown in the accompanying drawing, is to be interpreted as illustrative and not in a limiting sense.

I claim:

1. A construction of the character described 60 comprising a core with a winding thereon made of relatively small wire, said winding being supported by a bobbin made of insulating material having a sleeve-like portion through which the core extends and about which is the winding and 65 end members at the respective ends of the winding, said sleeve-like portion having extensions beyond said end members, a sheet metal member interposed between said core and said sleeve and having bendable portions capable of being bent 70 respectively over said extensions, two relatively heavy insulated lead wires having their insulated end portions resting each against one of said extensions and each having one of said bendable portions bent over the insulated end portion to 75

clamp it against the extension, for thereby anchoring said lead wires against said extensions, the ends of said relatively small wire winding being electrically connected respectively to bared 5 ends of said lead wires, the anchorage of which protects said relatively small wire ends against breakage and the insulation of said insulated lead wires against which said bendable portions are bent preventing said sheet metal member from 10 short-circuiting said two lead wires and from grounding either of them to said core.

2. A construction as claimed in claim 1 in which the extensions of said sleeve-like portion have cut away parts through which the bendable 15 portions of said sheet metal member extend from the core side of said extensions to the opposite side thereof.

3. A construction as claimed in claim 1 in which said sleeve-like portion of the bobbin is 20 made up of a plurality of sheet-like members, said end members having polygonal openings therein through which said sheet members extend, said sheet members and said end members having respectively interfitting parts, one of said 25 sheet members being longer than the spacing between said end members and projecting beyond each of the latter, thus to provide said extensions.

4. A construction as claimed in claim 1 in 30 which said sleeve-like portion of the bobbin is made up of a plurality of sheet-like members, said end members having polygonal openings therein through which said sheet members extend, said sheet members and said end members 35 having respectively interfitting parts, one of said sheet members being longer than the spacing between said end members and projecting beyond each of the latter, thus to provide said extensions, said longer sheet member having in its 40 projecting ends slots for the passage therethrough of the bendable portions of said sheet metal member.

5. In construction of the character described, in combination, a bobbin made of insulating material and comprising two axially spaced end 45 members and an intervening sleeve-like portion for receiving on the latter and between said end members a winding, said sleeve-like portion being extended beyond both of said end members 50 to provide end extensions, and a conductor-clamping element extending lengthwise of said sleeve-like portion and having bendable end members related respectively to said end extensions and bendable relative to the latter to hold 55 itself in assembled relation to said sleeve-like portion.

6. In construction of the character described, in combination, a bobbin made of insulating material and comprising two axially spaced end 60 members and an intervening sleeve-like portion for receiving on the latter and between said end members a winding, said sleeve-like portion being extended beyond both of said end members 65 to form end extensions, each end extension having a slot therein, and a sheet metal member extending through said sleeve-like portion and provided with bendable parts extending through the slots in said extensions for clamping conductors against the latter and for holding said sheet 70 metal member in place.

7. In construction of the character described, in combination, a bobbin made of insulating material and comprising two axially spaced end members and an intervening sleeve-like member 75 for receiving on the latter and between said end

members a winding, a conductor connected to said winding, one of the members of said bobbin having exposed opposed end portions with a bendable conductor-clamping element extending flatwise thereagainst, said clamping element having bendable end members respectively related to said opposed end portions and respectively bent over the latter to hold itself assembled thereto, said conductor being related to one of said bent elements and by it clamped and anchored against 10 movement.

8. In construction of the character described, in combination, a bobbin made of insulating material and comprising two axially spaced end members and an intervening sleeve-like portion 15 for receiving on the latter and between said end members a winding, said end members having four-sided apertures to form two pairs of opposed edges, said sleeve-like portion comprising two pairs of sheet members one pair of which is 20 longer than the desired spacing between said end members and each of said one pair having opposed recesses into which opposed edges of said two end members are received to hold the latter in spaced relation, the other pair of sheet members 25 and said end members having interfitting parts in the form of interfitting tongues and recesses and the contiguous edge portions of all of said sheet members having interfitting parts 30 whereby said sheet members are mutually supported against movement inwardly toward the axis of said bobbin, said end members holding said sheet members against movement outwardly from said axis, one of said sheet members extending at both ends beyond said two end members 35 to form two end extensions, two relatively heavy terminal conductors having electrical connection with the ends of said winding, and a single bendable clamping means extending along said extended sheet member to the respective 40 ends thereof and having clamping means at its two ends for respectively clamping the ends of the extended sheet member and said two heavy terminal conductors.

9. In construction of the character described, in combination, a bobbin made of insulating material and comprising two axially spaced end members and an intervening sleeve-like portion for receiving on the latter and between said end members a winding, said end members having 50 four-sided apertures to form two pairs of opposed edges, said sleeve-like portion comprising two pairs of sheet members one pair of which is longer than the desired spacing between said end members and each of said one pair having 55 opposed recesses into which opposed edges of said two end members are received to hold the latter in spaced relation, the other pair of sheet members and said end members having interfitting parts in the form of interfitting tongues and recesses and the contiguous edge portions of all of said sheet members having interfitting parts whereby said sheet members are mutually supported against movement inwardly toward the axis of said bobbin, said end members holding 60 said sheet members against movement outwardly from said axis, at least one of said sheet members being extended at at least one end beyond an end member, a relatively heavy terminal conductor in electrical connection with said winding, 65 and a sheet metal member resting against said extended sheet member and having two spaced clamping portions bendable against the opposite face of said extended sheet member, at least one of said bendable portions engaging the extension 70 75

of said sheet member and also clamping said terminal conductor thereto.

10. In construction of the character described, in combination, a core and a winding thereabout, 5 a sheet-like member of insulating material and a sheet metal member interposed between said winding and said core and both extending beyond an end of said winding, said sheet metal member being between said sheet member and 10 said core, and a terminal conductor for said winding and in electrical connection with the latter, said terminal conductor being clamped in position by a bent-over portion of said sheet metal member and said bent-over portion coating to 15 hold said sheet metal member against movement relative to said core.

11. In construction of the character described, in combination, a winding support of insulating material comprising two axially spaced end members 20 between which the winding is received and an insulating member extending between said end members for underlying the winding, said last-mentioned member being extended beyond both of said end members to provide end extensions, 25 and a sheet metal member underlying said member and its end extensions and having portions bent over said end extensions, and a conductor, one of said sheet metal portions engaging and clamping said conductor.

30. 12. In construction of the character described, in combination, a winding support of insulating material comprising two axially spaced end members between which the winding is received and an insulating member extending between said end 35 members for underlying the winding, a conductor, and a sheet metal member underlying said member and having end portions extending beyond said end members, said end portions of said sheet member being bent relative to said bobbin to hold 40 it self assembled thereto and at least one of said portions engaging and clamping said conductor.

13. In construction of the character described, in combination, a winding support of insulating material comprising two axially spaced end members between which the winding is received and an insulating member extending between said end members for underlying the winding, said last-mentioned member being extended beyond both of said end members to provide end extensions, 5 and a sheet metal conductor-securing member underlying said member and its extensions and 10 having bent end portions overlying said extensions for holding said sheet metal member and said insulating member together.

14. In construction of the character described, 15 a sub-assembly comprising a bobbin made of insulating material and comprising two axially spaced end members and an intervening sleeve-like portion for receiving on the latter and between said end members a winding, said sleeve-like portion being extended beyond both of said 20 end members to form end extensions, and a sheet metal member extending through said sleeve portion and provided with bendable parts at its ends 25 respectively overlying said end extensions for holding said sheet metal member in place and for clamping a conductor by at least one of said bendable parts.

15. In construction of the character described, 30 in combination, a winding support of insulating material comprising two axially spaced end members between which the winding is received and an insulating member extending between said end members for underlying the winding, said member being extended to expose at least two edges 35 thereof, a lead wire, and a sheet metal member lying along one face of said extended member and having clamping portions extending about said edges to the other face thereof for holding itself assembled to said extended member and for clamping said conductor in position. 40

JOHN C. JOOST.
